UNITED STATES PATENT OFFICE.

FREDERICK H. RAPLEY, OF NEW YORK, N. Y., ASSIGNOR TO PRESSED STEEL CAR COMPANY, OF PITTSBURG, PENNSYLVANIA, A CORPORATION OF NEW JERSEY.

METALLIC STREET-CAR.

SPECIFICATION forming part of Letters Patent No. 778,706, dated December 27, 1904.

Application filed December 26, 1903. Serial No. 186,678.

To all whom it may concern:

Be it known that I, FREDERICK H. RAPLEY, a subject of the King of Great Britain, residing at New York, in the county of New York 5 and State of New York, have invented a certain new and useful Improvement in Metallic Street-Cars, of which the following is a full, clear, and exact description.

The object of this invention is to provide an 10 incombustible street-car in which plate or sheet steel, pressed to shape, and rolled shapes are used throughout.

The invention comprises novel features of 15 construction in the underframe, in the platforms, in the body, in the seats, and in the roof, all as I will proceed now more particularly to set forth and finally claim.

In the accompanying drawings, illustrating 20 the invention, in the several figures of which like parts are similarly designated, Figure 1 is a side elevation with the lower portion 25 partly broken out. Fig. 2 is a vertical section substantially through the center of the car. Fig. 3 shows in the upper half a longitudinal section on line A B, Fig. 4, with the 30 floor-plates removed and in its lower half a top plan view with the roof-plates removed. Fig. 4 shows on the left-hand side a transverse vertical section substantially at the center of 35 the car and on the right-hand side an end elevation.

The underframe comprises a pair of longitudinal sills 1, made up of a number of sections or diaphragms disposed between trans- 40 soms or transverse diaphragms 2, to which they are riveted, and a series of intermediate continuous transoms or transverse diaphragms 3 of less depth than the transoms 2 are mounted above the sills 1. End sills 4, Fig. 2, of 45 angle cross-section, are connected with the sills 1 and their upper edges have angles 5 riveted to them on the inner sides. The floor-sheets 6 are riveted to these transoms and their longitudinal edges preferably are flanged, as at 7, Fig. 4, to aid in securing the side sheets hereinafter described.

The end platforms comprise longitudinal straight sills 8, which extend rearwardly be-

neath the end sills 4 and parallel with the longitudinal sills 1, and they are connected with 50 the end sills 4 by means of straps or hangers 9, and their top flanges are riveted to the bottom flanges of the longitudinal sills. The oblique platform-knees 10 are also secured to the end sills 4 by means of straps 11 and extend rearwardly beneath the sides of the car beyond the narrow transoms 3 and are riveted to the inturned bottom flanges of the side sheets, as indicated at 12, Fig. 3. These knees 10 are of bellied construction, substantially 55 as illustrated in the several figures of the drawings. The crown-pieces 13 are curved substantially as indicated in Fig. 3 and their sides are connected with the steps 14, as well as with the sills 8 and knees 10. The platforms are provided with floor-plates 15, riveted to the sills and the knees and to the crown-pieces. 60

All of the longitudinal sills, the transoms, the platform-sills, the platform-knees, end 70 sills, and the crown-pieces are preferably made of pressed-steel shapes, although rolled shapes may be substituted, and these several parts are made in the form of channels or angles set on edge with their flanges arranged 75 horizontally. The side posts 16 also are preferably pressed shapes of channel form with their lower ends curved inwardly, so as to preserve the ordinary outline of a street-car, and these side posts are riveted to the transoms and extend thence up to the eaves of the roof. The side sheets 17 have their lower portions curved to conform with the curves 80 of the side posts, and their lower edges are provided with inturned flanges 18 on a level 85 with and riveted to the lower flanges of transoms 2, so as to inclose the ends of these transoms and transoms 3. The side sheets are also riveted to the side posts. The lower and upper portions of the side sheets are provided, 90 respectively, with longitudinal stiffening-beads 19 and 20, and their upper edges are provided with inturned substantially horizontal flanges 21 at the window-openings to form window-sills. The side sheets, with their upper and lower flanges and as combined with 95

the transoms and post, constitute, in effect, plate-girders, which serve to carry the load. The fasciæ 22 are also metal sheets provided with stiffening-beads 23, inturned substantially horizontal flanges 24, forming lintels for the windows, and inwardly-projecting flanges 25 to receive the roof-sheets 26. These fasciæ are riveted to the side posts.

Attached to the side posts are rafters 27, 10 and attached to these rafters are deck-posts 28, to which in turn are connected the car-lines 29, and in order to reinforce the monitor-top erected on these deck-posts gusset-plates 30 are riveted to the deck-posts and 15 car-lines. The deck-sills 31 are pressed Z-bars, and the deck-plates 32 are also Z-bars, and these Z-bars are riveted to the deck-posts. The roof-sheets 33 are riveted to the car-lines 29. The inturned flanges of the deck-sills 20 and deck-plates form, respectively, the sills and lintels of the deck-windows.

The seats are made of metal and preferably in several parts—as, for example, the seat-bottoms 34, the seat-fronts 35, the backs 36, 25 and the seat-back tops 37—and these tops may be provided with horizontal portions 38, which coöperate with the horizontal portions 21 of the side plates to form the window-sills, it being understood that the seats in the instance 30 shown run longitudinally of the sides of the car. The seats are supported by legs or uprights 39 and bottom cross-bars 40 made of angles, the legs being riveted to floor-angles 41 and to the seat cross-bars 40 and the said 35 cross-bars being riveted to the side posts 16. The seat-fronts are riveted to the legs. In order to reinforce these legs 39, transverse gusset-plates 42 may be riveted to them and to the flanges of the side posts. The several 40 sections 35, 37, 38, and 39 of the seats may have lap-joints and be riveted together, as indicated in Fig. 4.

The dashers 43 may be metal sheets secured to floor-angles 44 and have their upper edges 45 provided with angles 45, and these angles are also secured to uprights 46, which support the platform-hood.

The platform-hood comprises a bow 47 made of angle metal, extending from end 50 post to end post of the side posts 16, and receiving hood-purlins 48, also made of angle metal, to which are secured the hood-sheets 49.

A transom bottom rail 50 is made of metal in the form of a box or pocket in order to receive the door-hangers and operating mechanism, and an angle 51 is riveted to this rail and to the roof-plates and purlins.

The upper deck end transom 52 has its frame of metal, preferably angles, erected 60 above the bottom rail. The ends 53 are made up of metal sheets and the end side posts, and they are preferably adapted, in connection with the transom bottom rail 50, to receive double sliding doors.

65 The interior and exterior finish of the car

may be of any suitable character, and especially such as will preserve the incombustibility of the structure.

As already sufficiently indicated, the whole body of the car, including the underframe, 70 platforms, superstructure, seats, and roof, may be made of steel plates of proper thickness and of sufficient strength to resist the strains to which it is subjected without undue increase in weight.

75 While the invention has been described in connection with a street-car, it is to be understood, of course, that it is not limited to that one style or class of cars, but is applicable to other styles or classes of cars, wholly or in 80 part, and with any necessary or desirable alterations.

What I claim is—

1. An all-steel street-car, comprising an underframe having longitudinal sills, transoms 85 to which said sills are riveted, sides flanged at their bottom edges and riveted to the transoms, side posts erected upon the transoms and to which the sides are riveted, fasciæ riveted to the side posts, and a monitor-roof 90 erected upon the side posts and fasciæ.

2. An underframe for cars, comprising a main series of one-piece transoms, longitudinal sills composed of diaphragms arranged between said main transoms and riveted to 95 them, a series of shallow one-piece transoms interposed between the main transoms and resting upon the longitudinal sills, and end sills.

3. A street-car underframe, comprising the 100 following metallic parts, namely, a series of main one-piece transoms, longitudinal sills composed of diaphragms arranged between said transoms and riveted to them, a series of secondary transoms secured to and above the 105 diaphragms, said several parts being of channel form, and end sills of angle form.

4. A street-car underframe, comprising the 110 following metallic parts, namely, a series of main one-piece transoms, longitudinal sills 110 composed of diaphragms arranged between said transoms and riveted to them, a series of secondary transoms secured to and above the diaphragms, said several parts being of channel form, and end sills of angle form, combined with floor-plates riveted to said transoms, and transverse angles connecting the floor-sheets and end sills.

5. A street-car, having a metallic underframe, and metallic sides, combined with end 120 platforms having channel-sills and knees riveted to said underframe.

6. A street-car, having a metallic underframe provided with end sills, and end platforms having platform-knees, and sills connected with said end sills by straps riveted to both.

7. A metal seat for cars, comprising legs, bottom cross-bars, a seat-front, a seat-bottom riveted to the front, a seat-back riveted to the 130

bottom, and a seat-back top riveted to the back, combined with a car-body structure.

8. A metal seat for cars, comprising legs, bottom cross-bars, a seat-front riveted to the 5 legs, a seat-bottom riveted to the front, a seat-back riveted to the bottom, and a seat-back top riveted to the back, combined with a car-body structure.

9. A metal seat for cars, comprising legs, 10 bottom cross-bars, a seat-front, a seat-bottom riveted to the front, a seat-back riveted to the bottom, and a seat-back top riveted to the back, and forming a portion of the sill of the adjacent window.

15 10. A railway-car, having metallic sides extending to the height of the windows and having their upper edges turned inwardly, combined with metallic seats having seat-back tops provided with outwardly-flanged edges 20 which coöperate with the upper edges of the side sheets to form the window-sills.

11. A metallic roof for cars, comprising deck-sills and deck-plates of Z-bar cross-section, the inwardly-extending flanges of said 25 bars forming respectively the sills and lintels of the deck light frame.

12. In a metal car-roof, a transom-bottom rail of substantially pocket form combined with the metal end sheets and end side posts.

13. In a metal car-roof, a transom-bottom 30 rail of substantially pocket form, combined with a platform-hood comprising purlins, a roof-sheet and a bow, and a transverse angle connecting the purlins and roof-sheet with the transom-rail.

14. In a metal car having side posts and seats constructed with legs, gusset-plates connecting said side posts and legs.

15. An all-steel street-car, having an underframe, side posts erected thereon, and side 40 sheets beaded and flanged at their upper ends and flanged at their lower ends and beaded longitudinally between the upper and lower ends and secured to the side posts.

In testimony whereof I have hereunto set 45 my hand this 24th day of December, A. D. 1903.

FREDERICK H. RAPLEY.
